AN ATTORNEY.

UNITED STATES PATENT OFFICE.

LEO PRANGE, OF BROOKLYN, NEW YORK.

DESIGN FOR A BUTTON.

SPECIFICATION forming part of Design No. 21,315, dated January 26, 1892.

Application filed December 18, 1891. Serial No. 415,548. Term of patent 3½ years.

To all whom it may concern:

Be it known that I, LEO PRANGE, of Brooklyn, Kings county, and State of New York, have originated and produced a new Design 5 for Buttons, of which the following is a specification.

I will describe a button embodying my design.

In the accompanying drawings, Figure 1 is 10 a front view of a circular button embodying my design. Fig. 2 is a perspective side view thereof.

My design comprises an angular figure A at the center of the button and figures B, representing jewels, arranged outside the same, constituting or embodying my design. I have 15 shown a jewel C arranged at the center of the button and four similar figures D arranged just inside the angular figure and about mid-

way between its corners. From the figures 20 D to the figure C bars or lines E extend. Thus, it will be seen, the angular figure is quartered. I have shown the several quarters as ornamented with fine lines running in different directions. I have shown a swell or 25 slight protuberance in the different quarters of the angular figure.

What I claim, and desire to secure by Letters Patent, is—

The design for a button, as herein shown 30 and described.

In testimony whereof I have signed my name to this specification in the presence of two subscribing witnesses.

LEO PRANGE.
